METHOD FOR THE MANUFACTURE OF
SHUTTLE BOXES

George W. Kretzschmar, Garfield, N. J.

Application June 5, 1936, Serial No. 83,737

2 Claims. (Cl. 29—170)

The present invention relates to multiple shuttle boxes and more particularly to a new and useful form of shuttle box and a method of making the same without casting operations or the use of molds as are now generally employed.

In weaving operations with a loom equipped with the standard form of shuttle box now in use, a substantial loss occurs in the weaving operation due to the fact that the thread from the shuttle frequently gets caught between the binder and the shuttle, in spite of the fact that a groove is usually provided in the side of the shuttle to avoid as far as possible breakage of thread due to this cause.

15 In the shuttle box of my invention means as hereinafter fully described are provided which substantially completely obviate the possibility of the thread being caught between the binder and the shuttle and as a result a very considerable increase in efficiency and saving of costs is obtained.

The method of my invention is adapted for the making of shuttle boxes having any desired number of cells, by which such cells may be made 25 with greater accuracy than by the methods heretofore used and by which the usual grinding and filing operations may be avoided.

One of the objects of my invention is to provide a form of shuttle box which is adapted to 30 prevent the thread from the shuttle getting caught or breaking during the passage of the shuttle from one side of the loom to the other.

Another object of the invention is to provide a novel form of shuttle box which is provided with 35 thread supporting means or channels in which the thread adjacent the shuttle may hang free or be supported so as to prevent the thread from being caught between the binder and shuttle in the movement of the shuttle out of the shuttle 40 box.

Another object of the invention is to provide a method for the making of shuttle boxes by which such boxes may be made with greater accuracy, at a higher speed and at lower cost than by the 45 methods heretofore employed.

Another object of the invention is to provide a method for the manufacture of shuttle boxes without casting and without the use of the usual 50 molds. By means of the method hereinafter described the operations of grinding and filing in the manufacture of shuttle boxes may be entirely eliminated and a stronger shuttle box construction is obtained.

55 Various other objects and advantages of the

invention will be apparent from the following detailed description thereof.

The various features of the invention are illustrated in the accompanying drawing showing the preferred embodiment of the invention, in connection with which the method hereinafter described may be carried out.

In the drawing:

Fig. 1 is a view in elevation of a form of shuttle box embodying my invention, in which the position of the shuttles in the cells is indicated in dotted lines;

Fig. 2 is a plan view of the shuttle box illustrated in Fig. 1 showing the position of the binder and binder holding spring;

Fig. 3 is an enlarged detailed sectional view showing the preferred form of channels, the view being taken on the section line 3—3 of Fig. 1;

Fig. 4 is an enlarged fragmentary plan view showing the end portions of the shuttle box and illustrating the method of welding the joints or contacting portions together;

Fig. 5 is a sectional view taken on the section line 5—5 of Fig. 4;

Fig. 6 is a view in perspective, partly in section taken on the section line 6—6 of Fig. 4; and

Fig. 7 is a fragmentary view of a shuttle leaving the shuttle box and showing the thread in looped position supported by the floor channel.

Referring more in detail to the drawing, the form of the invention illustrated is a two cell shuttle box, but it will be understood that a multi-cell box having any desired number of cells may be made in accordance with the method herein disclosed.

In making the shuttle box in accordance with the invention, the parts of the shuttle box are preferably first stamped out from strip steel and are then machined and formed to size. The various parts may then be readily assembled by holding the parts in the desired relationship by means of fixture clamps. The joints or parts are then welded together, preferably by electric welding, producing substantially perfect alignment of the parts, whereby the faces of the shuttle box 40 are smooth and do not require grinding or filing as has heretofore been necessary in order to produce sufficiently smooth faces.

It is to be emphasized that in carrying out this invention in its preferred form, the parts are not 50 assembled by the use of slots and lugs, but slots are formed only in the end pieces and the longitudinal members are connected to the cross members or end members so as to project half-way into the slots and the parts are then electrically 55

welded. The parts in which grooves are formed by joining the end pieces with the longitudinal parts so that the latter project into the slots are first fused together with a carbon arc and the grooves are then filled with weld or weld steel.

In order to prevent the thread connected to the shuttle from getting caught between the binder and the shuttle, a channel is provided adjacent to but slightly below each cell of the box which serves to catch and support the thread in position longitudinally adjacent to the shuttle during the portion of the travel of the shuttle when it moves in the box for its return stroke across the warp.

In forming the shuttle box in accordance with this invention the longitudinal members 2, 4, and 6 are first preferably stamped from strip steel, it being understood that the proper number of longitudinal members are employed depending upon the number of cells to be provided in the shuttle box. The end part 8 is also preferably stamped out, being bent so as to have the proper curvature at the portion 10 of the end plate. A suitable number of slots as 12, 14 and 16 are then formed in the end plate, the slots being of proper width so that the longitudinal members will exactly register with the slots. After the slots are formed, lug members 18 are preferably welded in place adjacent the intermediate and end slots, the lug members being of proper length so as to be adapted for forming openings 20 in which bushings may be inserted, if desired.

The plate member 22 is next formed, being preferably stamped out from strip steel and machined with the slots 23, 25 and 27 corresponding in number and size to those in the plate 8, so that when mounted in position the slots of the member 22 will register with the longitudinal members 2, 4, and 6 at the receiving end of the shuttle box. An end part 24 is also provided having slots as 26, 28, and 30 therein of a size adapted to register with the opposite ends of the longitudinal members 2, 4, and 6.

In attaching the guards or side strips 32, 34, 36, and 38, to the corresponding longitudinal members 2, 4, and 6, as shown more particularly in Fig. 6 of the drawing, the strips are welded through the full length thereof, the strips being set together half and half, that is, the longitudinal member as 4, for example, is placed so as to project half-way into the space or groove between the side members 36 and 34 and the groove 35 thus formed is filled with weld so as to make an integral union. In a similar manner the part 32 is attached to the longitudinal member 2, the space adjacent the adjoining edges being filled with weld so as to form an integral joint. In the same manner the strip 38 is united to the part 6 as will be clear from the drawing.

Referring now to Fig. 3 of the drawing, channels 40 and 42 are preferably provided adjacent the bottom of each cell so that in the movement of the shuttle out of the cell the thread will not be caught between the binder 44 and the shuttle 48. It will be understood that in connection with each cell of the shuttle box a binder as 44, shown more particularly in Fig. 2 of the drawing, is provided in order to arrest the movement of the shuttle as 48 after it enters the cell of the shuttle box. A friction material 52, which is generally a leather strip, is provided on the side of the binder adjacent the shuttle which assists in arresting the shuttle in its flight into the shuttle box.

The binders, as 44 and 46, are preferably hinged

or pivoted on lug members 45 which are preferably made integral with the longitudinal members 2, 4, and 6, the lugs being provided with removable bushings 47, as indicated in Figs. 2 and 4 of the drawing. The bushings are constructed so as to be readily replaceable when worn and thus serve to increase the life of the shuttle box.

Spring members 56 and 58 are provided adjacent each binder as 44 and 46 so as to maintain the binder in position for arresting the flight of the shuttle.

Referring to Fig. 3, it will be apparent that the eyelets 60 and 62 of the shuttles 48 and 50 are cleared by the binder members 44 and 46 so that the thread passing through the eyelets will be free to lay or be supported by the channels 40 and 42 in the floor members of the cells in the manner indicated more particularly in Fig. 7 of the drawing. The channels may obviously have any desired form, such as circular or angular in section or of other suitable form such as that shown in the drawing, so that the thread when contacting with the channel will move away from the floor of the cell, thus reducing the tendency of the thread to be caught in any part of the cell or mechanism.

In the making of the various parts of the shuttle box it will be obvious that the channels may be readily provided by stamping the longitudinal members which are to constitute the floor of the cells from strip steel so that the channel is formed in one operation in the required form in the longitudinal member, which member is of a size to register with the corresponding slot or slots in the transverse member or members so that with a welding operation the box may be immediately formed into its final form without filing or other finishing operations.

It will be understood that in the movement of the shuttle across the warp in the ordinary form of shuttle box there is a tendency for the thread to be caught by the binder and shuttle, even in spite of the fact that there is a groove provided in the shuttle so as to permit space for the thread to lay between the binder and the body of the shuttle. It is a relatively frequent occurrence, however, that the thread becomes entangled between the binder and the shuttle causing breakage of the thread. This is more apt to occur when the eyelet of the shuttle is at the far end of the box on one side of the loom, since in this position the thread becomes looped or doubled to a greater extent than on the other side of the loom where the eyelet is at the near end of the shuttle box, or nearer the warp threads.

By providing a channel of a form shown in Fig. 3 of the drawing, the thread from the shuttle is permitted to hang relatively free and serves to hold the thread in doubled relation, preventing entangling or moving into contact with the binder and adjacent face of the shuttle. The binders 44 and 46 are preferably made narrower than the standard form of binder in order to give additional space for the thread adjacent the shuttle in the movement of the shuttle in the shuttle box.

It will be apparent to those skilled in the art that various changes or modifications may be made in the method of manufacture and in the form of shuttle box as herein described without departing from the spirit or scope of the invention as defined in the claims.

Having thus described the invention, what is claimed is:

1. A method for the manufacture of a shuttle

box from steel parts including upper, lower and intermediate longitudinal members and longitudinal guard strips, which comprises machining the shuttle box parts to size, assembling the parts thereof by clamping the same in fixed relation so that the intermediate member engages guard strips on each side thereof leaving a slot portion into which a longitudinal portion of the said intermediate member projects part way and the upper and lower longitudinal members engage guard strips so as to leave a space adjacent each of the adjoining edges and filling the said slot portion and said spaces with weld material to unite the adjoining parts integrally together.

5 10 15

2. A method for the manufacture of a shuttle box from steel parts including upper, lower and intermediate longitudinal members and longitudi-

dinal guard strips for the cells thereof, which comprises machining the shuttle box parts to size, forming a channel in said lower and intermediate longitudinal members to provide support in the floor of each cell for the thread adjacent the shuttle, assembling the parts by clamping the same in fixed position so that the intermediate member engages guard strips on each side thereof leaving a slot portion into which a longitudinal portion of the said intermediate member projects part way and the upper and lower longitudinal members engage guard strips so as to leave a space adjacent each of the adjoining edges and filling the said slot portion and said spaces with weld material to unite the adjoining parts integrally together.
